UNITED STATES PATENT OFFICE

LEROY J. THOMPSON, OF GRAND RAPIDS, MICHIGAN

VENT DEVICE FOR FERMENTING RECEPTACLES

Application filed February 9, 1931. Serial No. 514,564.

The main object of this invention is to provide a vent device for casks, barrels or like receptacles which constitutes a combined stopper or bung and vent.

5 A further object is to provide a device having these features which is efficient for the purpose and is easily applied or used.

Objects relating to details and economies of my invention will appear from the description to follow. The invention is defined and pointed out in the claims.

A structure which is a preferred embodiment of my invention is illustrated in the accompanying drawing, in which:

15 Fig. 1 is a side elevation of my improved vent device.

Fig. 2 is a central longitudinal section on line 2—2 of Fig. 3, the vent being shown mainly in full lines.

20 Fig. 3 is a plan or outer end view.

Fig. 4 is an inner end view.

My improved vent device comprises a body portion 1 and a tapered bung or stopper portion 2, these being preferably formed integrally by turning from a piece of wood, or formed out of other suitable composition, the body portion being cylindrical and the stopper portion tapered.

25 The stopper portion has a central recess 3 in its inner end and radial grooves 4 opening to this recess. The purpose of this is that when the bung is driven into a cask or barrel its end may be well below the liquid level. The central recess, however, and these radial grooves insure a path of escape for the gases from the top of the liquid.

30 In the inner end of the body I form a seal chamber or receptacle 5 and I also make a longitudinal bore 6 which opens to the recess 3. A notch 7 connects the upper end of this bore with the chamber 5.

35 The U-shaped vent tube 8 has one arm longer than the other, the long arm 9 being sealed in the bore 6, the short arm 10 depending into the seal chamber 5. The bight portion 11 is arranged in the groove 7 so that it lies below the plane of the end of the body 1 and is thereby protected from blows as from a mallet or the like used in driving the stopper 40 into a bung hole.

The vent tube is provided with a check valve, this in the embodiment illustrated comprising a block-like body member 12 which has a central bore 13 into which the arm 10 of the vent tube project. The vent passage 14 opens to this bore 13 and at the top of the body member 12.

45 The flexible disk valve 15 is arranged on the vent tube to seat on the upper end of the valve body member, the retaining member 16 being 50 slidable on the arm 10 above the valve.

An overflow groove 17 is provided to determine the depth of water or sealing liquid in the chamber 5 although that is not an essential.

55 My improved vent device is very simple and economical in its parts and may be very conveniently used. The vent being embodied within the stopper structure, the necessity of sealing in of a separate vent tube as is quite common practice is avoided. Further, the likelihood of an imperfect closure is minimized.

60 I have illustrated and described my improvements in an embodiment which I have found highly practical. I have not attempted to illustrate or describe certain embodiments or adaptations as I believe this disclosure will enable those skilled in the art to embody or adapt the same as may be desired.

65 Having thus described my invention, what I claim as new and desire to secure by Letters Patent is:

1. A vent device comprising a cylindrical body member having an integral tapered stopper portion at its inner end, said stopper portion having a central recess with radial grooves opening to said recess, said body member having a seal chamber in its outer end and a bore extending from its outer end to said recess in said stopper, there being a notch connecting said bore to said seal chamber, a vent valve body disposed within said seal chamber and having a central bore, and a vent passage opening at the top of the valve body and to said bore, a U-shaped vent tube having one arm longer than the other arranged with its longer arm in said bore in said body member and its shorter arm depending into said recess and engaging with

- said valve body, the bight of said tube being engaged within said notch in the outer end of the body member and lying in the plane of the face of the body member, a flexible disk 5 valve arranged on said valve body to overlie said vent passage, and a valve retaining member loosely mounted on said tube above said valve.
2. A vent device comprising a cylindrical body member having an integral tapered stopper portion at its inner end, said body member having a seal chamber in its outer end and a bore extending from its outer end to the inner end of said stopper, there being 10 a notch connecting said bore to said seal chamber, a vent valve body disposed within said seal chamber and having a central bore, and a vent passage opening at the top of the valve body and to said bore, a U-shaped vent 15 tube having one arm longer than the other arranged with its longer arm in said bore in said body member and its shorter arm engaged with said valve body in said sealed chamber, the bight of said tube being engaged 20 within said notch in the outer end of the body member and lying in the plane of the face of the body member, a flexible disk valve arranged on said valve body to overlie said vent passage, and a valve retaining member 25 loosely mounted on said tube above said valve.
3. A vent device comprising a cylindrical body member having an integral stopper portion at its inner end, said stopper portion having a central recess with radial grooves 30 opening to said recess, said body member having a seal chamber in its outer end and a bore extending from its outer end to said recess in said stopper, there being a notch connecting said bore to said seal chamber, a U-shaped vent tube having one arm longer than the other arranged with its longer arm in 35 said bore in said body member and its shorter arm depending into said seal chamber, the bight of said tube being engaged within said notch in the outer end of the body member and lying in the plane of the face of the body member.
4. A vent device comprising a cylindrical body member having an integral stopper portion at its inner end, said stopper portion having a central recess with radial grooves opening to said recess, said body member having a seal chamber in its outer end and a bore extending from its outer end to said recess in 45 said stopper, a U-shaped vent tube having one arm longer than the other arranged with its longer arm in said bore in said body member and its short arm depending into said seal chamber.
5. A vent device comprising a cylindrical body member having an integral stopper portion at its inner end, said body member having a seal chamber in its outer end and a bore extending from its outer end to said 50
- recess in said stopper, there being a notch connecting said bore to said seal chamber, a U-shaped vent tube arranged with one arm sealed in the bore of said body member and its other arm depending into said seal chamber, the bight of said tube being engaged within said notch in the outer end of the body member and lying in the plane of the face of the body member, and a check valve 55 associated with said vent tube. 70
6. A vent device comprising a body member having a stopper portion at its inner end, said stopper portion having a central recess at its inner end and a seal chamber at its outer end, said stopper portion having a groove opening to said recess, a U-shaped vent tube sealed within said body member and opening to said recess with the outer end of the tube depending into said seal chamber, and a check valve associated with said vent tube. 75
- 80
7. A vent device comprising a body member having a stopper portion at its inner end and a seal chamber at its outer end, a U-shaped vent tube sealed within said body member and opening at the inner end of the stopper with the outer end of the tube depending into said seal chamber, and a check valve associated with said vent tube. 85
8. A vent device, comprising a cylindrical body member having an integral tapered stopper portion at its inner end, said body member having a seal chamber in its outer end and a bore extending from its outer end to the inner end of said stopper, there being a notch connecting said bore to said seal chamber, a vent valve body disposed within 90 said seal chamber and having a central bore, and a vent passage opening at the top of the valve body and to said bore, a U-shaped vent tube having one arm longer than the other arranged with its longer arm in said bore in 95 said body member and its shorter arm engaged with said valve body in said sealed chamber, the bight of said tube being engaged within said notch in the outer end of the body member and lying in the plane of the face of the body member, and a check valve associated with said vent tube. 100
- 105
- 110
- 115
- 120
- 125
- 130
- In witness whereof I have hereunto set my hand.
- LEROY J. THOMPSON.
